GEORGE L. BLANCHARD, OF CALEXICO, CALIFORNIA, ASSIGNOR TO J. G. BRITTINGHAM

DEFIBRATING APPARATUS AND PROCESS

Application filed April 29, 1929. Serial No. 358,998.

This invention relates to a method and apparatus for defibrating cotton seed hulls.

Various attempts have been made to adapt different grinding apparatuses and processes to the work of defibrating cotton seed hulls. The hammer mill which is ordinarily used for the purpose of grinding corn, alfalfa and other materials has been suggested for this purpose. Generally, this mill has hitherto been used in such a manner that the hammer blades whirl the material around an annular path, a portion of which path is provided with an outlet screen sufficiently small to permit only the fibers and powdered hull to escape. An air current is applied through the screen to hold the fiber against the outlet screen and to draw the fiber therethrough. The capacity of such a process and apparatus is small, a large amount of power is required, and the fibers contain an excessive amount of powdered hull which it is difficult to separate properly from the fiber.

Even when a further outlet screen is provided around the annular path of larger openings for escape of only partially powdered hulls, and the path is enlarged at that point, only part of the hulls are discharged from such screen in a single revolution and the greater part of the hulls partially or entirely separated from fibers are repeatedly returned to the fiber outlet screen clogging the machine greatly reducing the capacity of the machine, and at the same time, greatly increasing the powder content of the discharged fiber.

It is the general object of the present invention to provide an apparatus and process of defibrating cottonseed hulls which will possess a greater capacity, require less power, and provide a superior product containing less powdered hull than the apparatuses and processes heretofore used for that purpose.

More particularly, it is the object of the present invention to provide an apparatus and process of defibrating cottonseed hulls which will pass the hulls substantially only once over the fiber outlet screen, and will mainly prevent the defibered hulls from returning to the fiber outlet screen.

A further object of the present invention

is to provide an independent zone for holding the hulls after they have been defibered and to provide a separate means from the hulls scraping hammers or blades for holding the hulls in said zone until they are properly reduced in size for discharge from the apparatus and process.

It is a further object to provide a communication between the second or hull discharging and grind zone and the fiber outlet zone in which an air current is provided operative to return to the fiber outlet zone any fiber entrained in the hulls in said zone and the small amount of fibers that may be separated from the hulls in the further grinding on subdivision of the hulls which takes place in said hull outlet zone.

Various further objects and advantages of the present invention will appear from a description of the preferred form of a process and apparatus embodying the invention. For this purpose, there has been hereafter described a preferred form or example of a process and apparatus embodying the invention. The description is given in connection with the accompanying drawings, in which:

Figure 1 is a plan view partially in section of an apparatus embodying the invention.

Figure 2 is an elevation partially in section, and

Figure 3 is an enlarged view of one of the hammer or cutter blades.

Referring to the drawings, 2 indicates a chute by means of which cottonseed hulls can be fed to the apparatus. The apparatus contains a main chamber 3, the lower part of which is closed by semi-circular screen 4 of which contains openings approximate $\frac{1}{2}$ of an inch in size, which are of sufficient size so that the fibers separated from the hulls may pass, but of insufficient size to pass the hulls themselves except when the hulls have been reduced to a powder.

This lower portion of the chamber 3 constitutes a fiber screening and separating zone.

Revolvably mounted in the chamber 3 with its axis corresponding substantially to the axis of the semi-circular screen 4, is a hammer

mill member 5 preferably composed of a steel cylinder 6 formed of discs 7 and rods 8. On the rods 8 are pivoted hammer blades or cutters, 9, of thin metal, the plains of which cutters 9 lie perpendicular to the axis of that of the cylinder. Several of the blades 9 are positioned between each disc 7 of the cylinder and together these blades 9 cover most of the area of the cylinder.

10 The blades 9 operate as hull scooping members and to facilitate this action are preferably serrated at their edges, as indicated at 10. Each blade is provided with two openings 11, by means of which they may be pivoted on the rods 8 so that when desired, they may be reversed and their opposite edges used in the hull severing operation.

15 A roughened guide 14 is placed in the upper part of the main chamber 3 to direct the hulls towards the hammer cylinder. The hammer cylinder revolves counter-clockwise as viewed in Figure 2 and external of the mixing chamber is indicated a pulley 15 by means of which the hammer cylinder may be 20 rapidly revolved in operation.

25 Below the fiber screen 4 there is provided a suction chamber 16 which reduces to a line 17 connected to a suction fan 18 by means of which a current of air may be applied downward through the fiber screen, the air entering chute 2 and also the hull outlet screen to be later described.

30 About the first quarter of the chamber, in which the hammer mill operates, serves as a feeding zone for feeding fresh hulls into the fiber scraping and screening zone. Such zone occupies about one-half of the chamber and the final quarter communicates with a hull reducing chamber 19. The hull reducing chamber 19 is mainly closed by a hull outlet screen 20 of comparatively coarse outlets and around the screen, but spaced therefrom, is a baffle 21 which operates as a guard to 35 direct the hull particles ejected from the screen 20 downwards.

40 Within the hull chamber 19 is provided a hull divider and ejector 21a in the form of a rotary beater with paddle blades 22. This beater is shown as provided external to the chamber 19 with a gear 23 engaging gear 24 on the hammer cylinder shaft by means of which it may be revolved.

45 The process of defibering cottonseed hulls as carried out in the apparatus is as follows: 50 The cottonseed hulls are fed preferably continuously through the chute 2. The hulls are picked up by the air currents and hammer blades and carried around to the fiber screen 4. Here the fibers of the hulls under influence 55 of the outgoing air current, holds the hulls against the screen and they travel slowly compared to the speed of the blades 9. Almost immediately the fast revolving blades strip the fiber from the hulls while the hulls are still 60 maintained in comparatively large particles.

The fibers are drawn through the screen 4 while the comparatively fiber-free hulls, being of relatively large size, and because of loss of fiber less effected by the air current, are now forced by the blades 9 to the hull chamber 19. A baffle 25 and curved member 26 are provided for directing the hulls into chamber 19 and preventing their being whirled around again to the fiber screen 4.

70 Thus by the process of this invention whirling of the delinted hulls back to the fiber screen is prevented and accordingly, the cylinder may pick up a larger quantity of fresh hulls and the capacity of the machine is greatly increased.

75 In the chamber 19, the hulls are held and beat against the hull screens 20 by the paddles 22 which afford a better contact therewith than the surfaces of the blades 9.

80 The hulls thus ejected through the screen 20 are partially further divided in the chamber 19 by the beater 21a. The beater 21a is preferably rotated at a lesser R. P. M. than the hammer cylinder, so that any hulls ejected from the beater back on the hammer cylinder 85 will immediately be returned to the beater.

85 The small amount of fiber entrained with the hulls and any additional fiber liberated in chamber 19 are drawn by air current entering the hull screen 20 to the fiber screen 90 4 and pass out said screen. Only lintless hulls thus escape the hull screen.

95 A considerable saving of power is effected by the process and apparatus of this invention due to the fact that the hulls are immediately discharged from the fiber screen 100 after they are delinted and keep from returning as a whirl thereto. Moreover, the fiber obtained is comparatively free of powdered hulls.

105 While the particular form or example of apparatus and process embodying the invention herein described is well adapted to carry out the objects of the invention, various modifications and changes may be made and the invention is not limited to the particular form illustrated, but includes all such modifications and equivalents as come within the scope of the following claims.

110 I claim:

115 1. A process of defibrating cottonseed hulls which comprises, passing the hulls to a fiber screening zone, there scraping the fiber from the hulls, removing the fibers from the zone by means of an air current, immediately ejecting the fibers from the zone as they are delinted, and passing the hulls to a hull screening zone, there beating the hulls.

120 2. A process of defibrating cottonseed hulls which comprises, passing the hulls to a fiber screening zone, there scraping the fiber from the hulls, removing the fibers from the zone by means of an air current, immediately ejecting the fibers from the zone as they are delinted, and passing the hulls to a hull screening zone.

- ing zone, there beating the hulls while re-
turning fiber from the hull screening zone
to said fiber screening zone by means of an
air current.
5. 3. A process of defibrating cottonseed hulls
which comprises, passing the hulls to a fiber
screening zone, there scraping the fibers from
the hulls, removing the fibers from the zone
by means of an air current, immediately eject-
10 ing the fibers from the zone as they are de-
linted, and passing the hulls to a hull screen-
ing zone, there beating the hulls, and restrain-
ing hulls from returning to said fiber screen-
ing zone.
15. 4. A process of separating fiber from cot-
tonseed hulls which comprises, severing the
fiber from the skins by the action of hammer
blades at a fiber screen, holding the fiber con-
taining hulls at said screen against the ac-
20 tion of said blades by passing an air current
through the screen, said air current remov-
ing fibers through the screen, immediately
passing delinted hulls from said screen against
25 an air current capable of returning
fibers thereto, said hulls passing to a hull
screen, mainly preventing said hulls return-
ing to said fiber screen and beating the hulls
through said hull screen.
5. A process of delinting cottonseed hulls
30 which comprises, passing hulls to a fiber
screen and also to hull screen, scraping the
hulls at the fiber screen, beating hulls at the
hull screen, and applying a current of air
through the hull screen to the fiber screen so
35 as to maintain the fiber and fiber containing
hulls at said fiber screen while permitting
delinted hulls to be carried therefrom to said
hull screen.
6. An apparatus for delinting fibers from
40 hulls which comprises, a main chamber hav-
ing a fiber outlet screen, a rotor having ham-
mer blades revolvable in said chamber, means
for passing an air current through said
screen, a hull discharge chamber positioned
45 to receive hulls from said fiber screen and
hold the hulls from whirling again to said
fiber screen, and a beater for the hulls in said
hull chamber.
7. An apparatus for delinting fiber from
50 cottonseed hulls comprising, a rotor having
hammer blades operative for scraping fiber
from the hulls, a screen for passing only fiber
and powdered hulls surrounding a portion
of said rotor, means for passing a current
55 air through said screen at such a rate as to
hold the fiber containing hulls at said screen,
sufficient time to be delinted by the blades
of said rotor, but at insufficient rate to hold
delinted hulls at said screen, a hull beater
60 chamber for receiving hulls from said fiber
screen, a hull discharge screen for said cham-
ber, and a revolvable hull beater in said
chamber.
8. An apparatus for delinting fiber from
65 cottonseed hulls comprising, a rotor having
hammer blades operative for scraping fiber
from the hulls, a screen for passing only fiber
and powdered hulls surrounding a portion
of said rotor, means for passing a current
70 air through said screen at such a rate as to
hold the fiber containing hulls at said screen,
sufficient time to be delinted by the blades
of said rotor, but at insufficient rate to hold
delinted hulls at said screen, a hull beater
75 chamber for receiving hulls from said fiber
screen, a hull discharge screen for said cham-
ber, and a revolvable hull beater in said
chamber, and a baffle to prevent the hulls
whirling back to the fiber screen.
9. An apparatus for delinting fiber from
80 cottonseed hulls comprising, a rotor having
hammer blades operative for scraping fiber
from the hulls, a screen for passing only fiber
and powdered hulls surrounding a portion of
said rotor, means for passing a current of
85 air through said screen a sufficient time to
be delinted by the blades of said rotor, but
at insufficient rate to hold delinted hulls at
said screen, a hull beater chamber for receiv-
ing hulls from said fiber screen, a hull dis-
90 charge screen for said chamber, and a revolv-
able hull beater in said chamber, the rotor
revolving more rapidly than the beater, and
a baffle to prevent hulls whirling back to said
fiber screen.
